LUBRICATING SYSTEM FOR INTERNAL COMBUSTION ENGINES

Filed July 23, 1931

UNITED STATES PATENT OFFICE

BURT N. PIERCE, OF NEW YORK, N. Y., ASSIGNOR TO EMEROL MANUFACTURING CO., OF NEW YORK, N. Y., A CORPORATION OF ILLINOIS

LUBRICATING SYSTEM FOR INTERNAL COMBUSTION ENGINES

Application filed July 23, 1931. Serial No. 552,727.

This invention relates to certain new and useful improvements in lubricating systems for internal combustion engines as disclosed in the application filed by Vernon W. Thompson and Burt N. Pierce, December 8, 1930, Serial Number 500,928 and is a companion application of an application filed even date herewith, the object being to provide a novel form of housing formed of three sections which can be readily assembled so as to properly position the diaphragm.

Another object of my invention is to provide novel means for securing the various sections of the housing together so that when assembled, spaced chambers will be formed in the housing separated by a diaphragm having an apertured plug into which is adapted to extend an adjustable needle valve.

Other and further objects and advantages of the invention will be hereinafter set forth and the novel features thereof defined by the appended claims.

In the drawing,

Figure 1 is a front elevation of a housing used in connection with a lubricating system as disclosed in a lubricating system relying on the suction of the engine for drawing fuel from a source of supply to the cylinders of the engine;

Figure 2 is a rear elevation;

Figure 3 is a vertical section;

Figure 4 is a vertical section taken at right angles to that of Figure 3; and

Figure 5 is a horizontal detail section showing the various sections of the housing.

In carrying out my invention I employ a back section 1 with an intermediate section 2 and a front section 3, said front section being provided with a sight opening 3'. The back section is provided with an inlet nipple 4 and the intermediate section with an outlet nipple 5 through which the lubricant is adapted to pass in its passage from the source of supply to the cylinders of the engine.

The back section is provided with an annu-

lar seat 6 in which is arranged a washer 7 against which is arranged a flexible diaphragm 8 having an apertured plug 9 carrying a drip spoon 10 against which the intermediate section 2 is clamped by screws 11 so as to clamp this back and intermediate sections firmly together.

The intermediate section engages a washer 12 carried by the front section and this washer is provided with apertures registering with threaded sockets into which are adapted to extend some of the screws 11 for clamping the three sections together. Some of the screws 11 only pass into threaded sockets formed in the intermediate section 2 while other screws pass through apertures formed in the intermediate section into the threaded sockets 13 formed in the front section as clearly shown in Figure 5 which allows the back section and intermediate section to be connected together first and placed in position within the cup-shaped front section.

The intermediate section carries a pivoted arm 14 provided with a needle valve 15 cooperating with the apertured plug 9, said arm being engaged by a spring 16 which holds the end of said arm into engagement with a cam 17 carried by a shaft 18 slidably and revolvably mounted in a stem 19 carried by the intermediate section, said shaft having a cap 20 carried by its upper end, which cap is preferably formed hollow and surrounded by a coil spring 21 between the stem 19 and the inner wall of the cap in order to hold the cap in extended position. A spring 21 engages a washer 22 disposed over the end of the stem 19 so as to hold it firmly against the stem to form a liquid tight joint.

The front housing is provided with a notch 23 to receive the outlet nipple 5 and a notch 24 to receive the stem 19, said stem carrying a pointer 25 held in its adjusted position by said notch 24 and adapted to cooperate with designations formed on the sleeve of the cap, which designations are arranged from 0 to 5

so that by turning the cap in either direction the needle valve will be adjusted so as to control the passage of lubricant through the apertured plug of the diaphragm.

5 In assembling a housing as shown the back section and intermediate section are secured together by the screws 11. The arm 14 is placed in position between the bearings and the pivot pin placed in position within the 10 bearings and a lug 26 carried by the front of the housing then extends into the path of travel of said pivot pin so as to lock it in adjusted position. The spring is then placed 15 in position and when the front section of the housing has been placed in position and some of the screws forced into the sockets 13, the free sections will be held tightly together to form a liquid tight joint between the various parts in order to form two chambers 20 separated by a flexible diaphragm, which diaphragm is flexed by the suction of the engine so as to control the passage of lubricant from the source of supply and in its passage from the source of supply to the cylinders of 25 the engine, it drops off the spoon 10 in front of the sight opening and the operator can at all times ascertain the amount of lubricant being fed to the cylinder of the engine and can increase or decrease the supply by adjusting 30 the cam which shifts the position of the needle valve 15 in respect to the apertured plug of the diaphragm.

What I claim is:

1. In a lubricating system for internal combustion engines, a sectional housing 35 formed of a back section, an intermediate section and a cup-shaped front section, a diaphragm secured between the back section and the intermediate section having an aperture through which lubricant is adapted to pass from the source of supply to the cylinders 40 of the engine, said back section being provided with an inlet and the intermediate section with an outlet, said front section being provided with a sight opening, packings arranged 45 between said sections and means for securing said sections together to form a liquid wall between said sections.

2. In a lubricating system for internal combustion engines, a sectional housing 50 formed of a front section, an intermediate section and a back section, a diaphragm secured between said back section and intermediate section having an aperture through which lubricant is adapted to pass, a pivoted 55 arm carrying a needle valve mounted within said housing cooperating with the aperture of said diaphragm, a cam engaging said arm, a shaft upon which said cam is mounted, a cap carried by said shaft, a washer surrounding 60 said shaft and a spring arranged within said cap engaging said washer forming a liquid tight joint around said shaft.

3. In a lubricating system for internal combustion engines, a sectional housing com-

prising a back section, an intermediate section and a cup-shaped front section having a notch in its flanged portion thereof, a diaphragm secured between said back section and an intermediate section, a pivoted arm 70 carrying a needle valve cooperating with the aperture of said diaphragm, said intermediate section being provided with a stem portion, a shaft slidably mounted in said stem portion carrying a cam engaging said arm, a cap carried by said shaft having numerals and a pointer comprising a hub portion surrounding said stem and adapted to be held in its adjusted position above the notch of 75 said front section when said sections are 80 assembled.

4. In a lubricating system for internal combustion engines, a sectional housing having a flexible diaphragm provided with an aperture through which lubricant is adapted 85 to be drawn by the suction of the engine, a needle valve cooperating with the aperture of said diaphragm, a shaft carrying a cam for adjusting the position of said needle valve and means for indicating the position 90 of said cam for determining the position of said needle valve.

5. A lubricating system for internal combustion engines, a housing having an inlet and an outlet and a sight feed opening, a flexible diaphragm arranged in said housing having an aperture adapted to be moved by the suction of the engine, a needle valve 95 operating with said aperture and means for adjusting the position of said needle valve.

6. A lubricating system for internal combustion engines, a housing having an inlet and an outlet and a sight feed opening, a flexible diaphragm arranged in said housing having an aperture adapted to be moved by the suction of the engine, a needle valve 100 operating with said aperture, means for adjusting the position of said needle valve and means for indicating the position of said adjusting means.

7. In a lubricating system for internal combustion engines, a housing having a sight feed opening, a flexible diaphragm mounted in said housing having an aperture adapted 105 to be flexed by the suction of the engine, a needle valve cooperating with said aperture, means for adjusting the position of said needle valve in respect to said aperture and means for indicating the position of said needle valve in respect to said aperture comprising a revoluble head having numerals from 0 to 5 with a stationary pointer.

8. In a lubricating system for internal combustion engines, a housing composed of three sections, detachably connected together, an apertured diaphragm arranged between two of said sections, one of said sections being provided with an annular flange having a notch and a pointer adapted to seat 125 130

in said notch when said sections are assembled.

9. In a lubricating system for internal combustion engines, a sectional housing having an apertured diaphragm disposed therein, a needle valve cooperating with the aperture of said diaphragm, an arm upon which said needle valve is universally mounted, a cam for operating said arm, a shaft for operating said cam, a head carried by said shaft having numerals from 0 to 5 thereon and a pointer carried by said housing at one side of said head.

In testimony whereof I hereunto affix my
15 signature.

BURT N. PIERCE.
